STEAM PURIFIER AND SKIMMER

Verl E. McCoy, La Grange, and Homer H. Richardson, Western Springs, Ill.

Application January 27, 1938, Serial No. 187,232

6 Claims. (Cl. 122—459)

This invention relates to a steam purifier and skimmer and is particularly adapted for use with locomotive boilers, although it may be used with equal efficiency with various other types of steam boilers.

Locomotive boilers usually are provided with a steam dome and a steam outlet pipe arranged to deliver steam therefrom to the cylinders of the locomotive. Most of the steam liberated in locomotive boilers comes from the water at the rear end of the boiler and from over the top of the fire box. This is due to the well understood circulation within the boiler caused by heat absorption through the fire box sheets. In the ordinary locomotive boiler the steam liberated from over the fire box passes directly to the dome without having time for moisture entrained in the steam, as a result of violent ebullition in the area over and adjacent the fire box, to settle out.

It is an object of the present invention to provide a purifier and skimmer adapted to remove the entrained moisture and impurities from the steam as it passes from the rear of the boiler to the steam dome and thence to the locomotive cylinders. This is accomplished partially by providing for a longer than normal travel of the steam to the steam dome which assists greatly in precipitating the entrained moisture. The device is also arranged effectively to remove foam bubbles—as opposed to entrained moisture—and also remove the moisture and dissolved solids suspended in the steam. The impurity laden moisture and foam is collected in a suitable container and is removed therefrom by means of an automatic blow-off forming part of the instant invention.

The particular embodiment shown and described herein comprises a U-shaped baffle with the closed end under the dome of the locomotive boiler and the open end extending forwardly toward the front end of the boiler. This baffle forms a U-shaped vertical partition around the rear of the steam dome with its parallel sides extending forwardly some distance from the dome and provides two oppositely disposed steam paths toward the front of the boiler from the crown sheet of the fire box where most of the steam is generated. The partition or baffle is preferably secured to the top boiler plates and depends therefrom to a point somewhat below the normal water line of the boiler. The steam, therefore, passes from the rear of the boiler through the oppositely disposed paths toward the front of the boiler and returns to the dome through the open end of the baffle. During this

long travel of steam the moisture settles out to a considerable extent.

A transverse trough is positioned on each side of the horseshoe baffle and the sides of these troughs extend slightly above the water level to provide baffles in the path of the steam. The troughs are open at the top and preferably so arranged that the top edges are approximately two inches above the normal top water line in the boiler. Also they are positioned longitudinally approximately on the central vertical plane of the body of water in the boiler so that operation up or down hill, or sudden stops or starts will not cause water to spill into the trough. The troughs accumulate the moisture, bubbles and dissolved solids which are precipitated from the steam as it passes through the channel to the front of the U-shaped baffle from which it returns to the steam dome. The troughs also act as skimmers and collect the scum and bubbles from the surface of the water and the accumulation is then automatically blown off in a manner to be later described.

An automatic steam blow-off is provided for blowing off the accumulation from the troughs. This blow-off is controlled by means of a valve in the blow-off conduit. The valve is in turn controlled by steam pressure admitted thereto by a float in one of the troughs. The float controls the admission of steam to a suitable pressure conduit leading to the blow-off valve.

The troughs are connected together by means of an equalizing pipe having a connection leading to the blow-off valve so that when the skinned water and impurities accumulate in the troughs to an extent sufficient to operate the float, the blow-off valve is opened. The blow-off is directed to a steam separator, preferably located on the top of the boiler. The steam separator may be of the usual centrifugal type and arranged to discharge the steam upwardly therefrom and to discharge the water and impurities downwardly onto the road bed, or in any other desired direction.

A particular object of the invention is to provide an efficient skimmer and purifier having an automatic blow-off and which will be cheap to manufacture, easy to install and will not interfere materially with the inspection of the interior of the boiler and the repair and usual servicing thereof.

The invention also provides means whereby water may be delivered to the boiler in the form of a spray and wherein all of the steam flowing around the baffle on the way to the dome will

pass through this water spray and any entrained bubbles will be broken.

Further objects will be apparent from the specification and the appended claims.

In the drawings:

Fig. 1 is a longitudinal sectional view of a boiler incorporating one embodiment of the invention. The baffle and troughs and blow-off connections are shown in full lines;

Fig. 2 is a top view of a boiler, partially in section with the top plate broken away to disclose the baffles and skimmers and associated elements; and

Fig. 3 is a transverse sectional view taken on a line substantially corresponding to line 3-3 of Fig. 2.

Referring to the drawings, the embodiment illustrated comprises the usual locomotive boiler 1 which may be provided with a fire box 2 having the usual crown sheet 3 and flue sheet 4. Flues 6 are connected to the flue sheet in the usual manner. Only a few of the flues are shown as the boiler may be of any usual construction well known in the art. The boiler is provided with a dome 7 and a U-shaped baffle member or partition 8 is positioned immediately thereunder. The baffle 8, which may for convenience be called a horseshoe baffle, forms a U-shaped partition around the rear of the dome and depending from the top boiler sheets to which it may be secured by any suitable means.

The horseshoe baffle is open at its forward end to provide a steam passage 9 leading to the dome, and its rear end is closed by an arcuate door 10 which may be secured in any suitable manner as by key bolts. The door may be hinged or bolted or otherwise secured in any suitable manner whereby it may be opened or removed for inspection of the fire box stays, or, for any necessary inspection or repair of the boiler. The partition formed by the baffle 8 extends downwardly some distance below the top water line of the boiler, preferably about two or three inches, and a laterally extending trough 11 is provided on each side thereof. These troughs are preferably V-shaped in cross section substantially as illustrated in Fig. 1, with the lowest point toward the front of the boiler and substantially below the water level.

The side walls of each trough extend upwardly above the water level preferably approximately two inches, or any suitable height which will enable the passage of steam without restriction and at the same time provide suitable baffles for moisture or bubbles in the steam. The troughs are preferably rigidly secured to the horseshoe baffle and to the sides of the boiler so that they extend laterally as shown in Fig. 3 and provide a suitable steam passage 12 thereover on each side of the horseshoe baffle 8.

It will be apparent that with this construction, steam, which is ordinarily generated over the crown sheet 3, must necessarily pass forwardly through the passages 12 and over the edges of the troughs which form the previously mentioned baffles, and thence around the forward ends of the horseshoe baffle and rearwardly into the dome where it may be passed to the steam cylinders through the usual steam conduit 13. At the same time the troughs 11 provide efficient skimmers.

A level-equalizing pipe 14 connects the troughs 11, and an automatic blow-off is provided between the troughs so that the precipitation therein may automatically be blown off through

the equalizing pipe whenever the precipitation reaches a predetermined depth. The automatic blow-off comprises a valve 15 which controls a blow-off conduit 16, which conduit communicates

5 between the equalizing pipe 14 and the usual centrifugal separator 17, the latter being preferably mounted on top of the boiler and arranged to discharge the steam preferably upwardly. The separator is also provided with a downwardly 10 extending conduit 18 for discharging water downwardly to the road bed. The blow-off valve 15 is automatically controlled by steam pressure from the dome, the steam being directed through a conduit 20 as required to operate the 15 valve 15. A float 19 is mounted on a suitable arm arranged to open a valve 21 controlling the pressure pipe 20, and which arm extends into one of the troughs as shown in Fig. 3. Whenever the precipitated moisture and scum in the 20 troughs reach a predetermined height, the float 19 opens the valve 21 which in turn causes steam pressure to open the blow-off valve 15 and the water is discharged from the troughs and, of course, the valve closes as soon as a predetermined amount of water is blown off.

A water inlet to the boiler is provided and preferably comprises a valve 22 located in front of the steam dome 7 and having inlet pipes 23 connected thereto. The valve 22 communicates with an arcuate discharge pipe 24 provided within the boiler adjacent the top as illustrated in Fig. 3 and this inlet pipe is preferably provided with a plurality of perforations 25. These perforations are so located that the water is discharged in a spray substantially covering the path of the steam toward the front end of the horseshoe baffle plate and through which the steam must pass to enter the dome.

It will, therefore, be apparent that the spray 40 from the pipes 24 will effectively clean the steam and particularly will puncture bubbles which pass over the trough and do not collect therein, and are obliged, therefore, to pass through the fresh water spray from the inlet pipe. These 45 foam bubbles are broken and precipitated with the spray.

The position of the troughs 11 outside the horseshoe baffle and the door 10 at the end of the baffle permits accessibility to the boiler without 50 breaking any water joints other than the dome cover itself.

An efficient horseshoe baffle is provided whereby the steam is compelled to pass from the point of generation to the front of the boiler 55 and is then returned to the dome. This longer travel greatly assists in dropping out entrained moisture and dissolved solids. An efficient float control blow-off is provided in combination with the above described device and this blow-off 60 may be from skimmer troughs substantially at the water line of the boiler.

Furthermore an effective fresh water spray is provided which effectively assists in removing 65 any impurities and causes precipitation of any bubbles in the steam.

It will be apparent that with the present invention comparatively dry steam may be provided in the dome 7 and at the same time the 70 device acts as an effective skimmer and cleaner and automatic blow-off, effectively removing moisture and impurities from the steam.

Modifications may be made without departing from the spirit of the invention. It is desired, therefore, that the invention be limited only by

the prior art and the scope of the appended claims.

Having thus described this invention, what is claimed and desired to be secured by Letters Patent is:

1. The combination with a locomotive boiler having a crown sheet with a normal water level above said crown sheet and a steam service outlet in advance of said crown sheet and substantially on the transverse central plane of the body of water in said boiler, of a substantially U-shaped partition depending from the top boiler plates to below the water line with its closed end communicating with said outlet and its open end remote from said crown sheet to provide an elongated passage on each side of said boiler and communicating with the front thereof, a foam skimmer in each passage below the water line and comprising a trough-like container extending laterally from each side of said U-shaped partition to the adjacent boiler plate and having its side walls extending above the water line to form baffles, an equalizing conduit between said troughs, a float in one of said troughs, and means controlled by said float to intermittently discharge the scum and impurities collected by both skimmers.

2. In a locomotive boiler having a crown sheet with a normal water level above said crown sheet, the combination with a steam dome substantially on the central transverse plane of the body of water in said boiler and having a service outlet therefrom, of a substantially U-shaped baffle partition depending from the top boiler plates to below said water line with its closed end forming substantially a downward extension of the wall of said dome and with its open end extended forwardly a material distance from said dome to form a central passage substantially the same width as said dome, said dome and baffle being positioned in the transverse plane of minimum disturbance of the water level during tilting or sudden stops and starts of said locomotive.

3. In a locomotive boiler having a crown sheet at one end with a normal water level above said crown sheet and a steam service outlet in advance of said crown sheet but adjacent thereto, a substantially U-shaped partition depending from the top boiler plates to below the water line with its closed end immediately below and communicating with said outlet and its open end remote from said crown sheet and said outlet to provide an elongated passage on each side of said boiler communicating with the front thereof, a foam skimmer trough extending laterally across each passage and transversely coextensive therewith below the water line and substantially on the central transverse plane of the body of water

in said boiler and having its side walls slightly above the water line, and means controlled by variations in the liquid level in said troughs to intermittently discharge the accumulations therein.

5. In a locomotive boiler having a crown sheet with a normal water level above said crown sheet, the combination with a steam dome substantially on the central transverse plane of the body of water in each boiler and having a service outlet therefrom of a substantially U-shaped baffle forming a partition around said dome inlet between the crown sheet and dome and forming substantially a depending continuation of the dome walls and extending below the water line to provide a steam passage on each side of said dome with the wings of said baffle extending a material distance forwardly of said dome, a trough-like skimmer receptacle in each side passage below the water line and extending transversely of each steam passage from the baffle to the adjacent boiler plate and having its transverse side walls extending above the water line to provide skimmer baffles, said skimmers being substantially on said central transverse plane, an equalizing conduit between said skimmers, a normally closed blow-off conduit leading from said equalizing conduit, and means in at least one of said skimmers and controlled by the liquid level therein to intermittently blow off the accumulation in said skimmers through said equalizing pipe.

30 5. In a steam purifier and boiler skimmer, the combination with means providing steam paths along each side of the usual boiler dome and a single return path to said dome, of a skimmer trough in each side path and transversely coextensive therewith and substantially on the central transverse plane of the body of water in said boiler, an equalizing conduit between said troughs, and means controlled by the fluid level in said troughs for automatically blowing off the accumulation therefrom.

45 6. In a steam purifier and boiler skimmer, the combination with means providing steam paths along each side of the usual boiler dome and a single return path to said dome, of a skimmer trough in each side path and transversely coextensive therewith and substantially on the central transverse plane of the body of water in said boiler, an equalizing conduit between said troughs, a steam controlled blowoff conduit from said equalizing conduit and having a blowoff valve outside said boiler, a float in one of said troughs, and means controlled by said float for intermittently directing steam to control said valve in response to variations in liquid level in said troughs.
